UNITED STATES PATENT OFFICE

CHARLES F. HANSELMANN, OF NEW YORK, N. Y.

SOUND-PRODUCING DEVICE

Application filed October 2, 1929. Serial No. 396,750.

This invention relates to sound producing devices, and relates more particularly to the class of sound producing devices used in toys and designed and adapted to be operated by the action of air.

The invention resides in the structural and functional improvements hereinafter fully described and illustrated in the accompanying drawing, in which

10 Figure 1 is a side view of a toy with one form of the device incorporated therein.

Fig. 2 is a section taken on the line 2—2 of Fig. 1.

15 Fig. 3 is an enlarged section through the device and showing portions of the bellows.

Fig. 4 is a view of the device looking in the direction indicated by the line 4—4 of Fig. 3.

Fig. 5 is a section taken on the line 5—5 of Fig. 4.

20 Fig. 6 is a plan view of a modified form of device.

Fig. 7 is a section taken on the line 7—7 of Fig. 6.

Referring now more particularly to Figs. 25 1 to 5 inclusive of the drawing, it will be apparent that there is shown a bellows type of toy commonly known as a "squeezum" toy consisting of a bellows 10 and a sound producing device 11 arranged within the bellows

30 and designed and adapted to be operated by air expelled from the bellows by squeezing the same. The bellows 10 in the present instance consists of two flexible plates or cardboard 12 which are glued together along their

35 marginal edges to form an airtight chamber 13. The cardboard members 12 are acted upon by a spring means not shown which yieldably maintains them in the chamber forming relationship. The construction and

40 arrangement is such that when the members 12 are brought together the air within the chamber 13 will be expelled therefrom for the purpose of operating the device 11.

The sound producing device 11 includes a 45 sound box 14 consisting of a base member 15 and a hollow member 16, both members being made of metal, and both being of circular shape. The base member 15 is crimped to present spaced ribs 17 between which a reed unit 50 is arranged. The hollow member 16 is se-

cured to the base member 15 in any suitable manner and in the present instance the marginal edge of the base member is turned inwardly over the marginal edge of the hollow member 16 as at 18. The reed unit consists 55 of a metal reed 19 and a tubi-form member 20, the reed being operatively secured in place on the member 20 in any suitable manner. The reed unit projects from the box 14, and the free end of the reed which vibrates being 60 outermost as shown most clearly in Figs. 3 and 4. The inner end of the member 20 is open to the interior of the box 14. The base member 15 has formed integral therewith a tubular member 21 which serves as a means 65 for attaching the device 11 to one of the cardboard members 12, and also for forming an air passage 22 for the device 11. The tubular member 21 is projected through a hole in the related cardboard member 12 and is crushed 70 down as at 23 to securely fasten the device 11 in place. It will now be understood that when the members 12 of the bellows 10 are pressed toward each other, air which has entered the chamber 13 will be expelled, and in so being 75 expelled will cause the reed 19 to vibrate thereby producing the sound; the air escaping from the box through the passage 22. In the form of the invention hereinabove described, the invention resides in the manner 80 of securing the reed unit in place by the structural features of the metal members 15 and 16 of the box 14, and in the manner of attaching the device 11 by the provision of the tubular member 21, which as stated, constitutes an 85 attaching means and also forms an air passage.

In Figs. 6 and 7 there is shown a modified form of sound producing device, which differs from the device 11 hereinbefore described, in that it includes a sound box 24 which is designed and adapted to change the sound pitch of the device. Accordingly, the box 24 consists of a base member 25 and hollow members 26 and 27. The reed unit 28 is 95 secured in place in the base member 25 in the manner set forth above. The hollow member 26 is fixedly secured to the base member 25, while the hollow member 27 is slidably connected with the base member 25 100

so as to be adjustable relatively to the hollow member 26, to vary the size of the air chamber of the box 24, for the purpose of changing the sound pitch of the device. It is to be understood that before this type of sound producing device is incorporated in a toy, the hollow member 27 will be set in such proper relation with respect to the hollow member 26 to produce the desired sound.

10 I claim:

1. A sound producing device having a box which forms an air chamber through which air circulates for the purpose of producing the sound, said box comprising a base member, a hollow member fixed to said base member, a second hollow member connected with said base member for fixed adjustment in relation to said fixed hollow member, to vary the size of said chamber, for the purpose of changing the sound pitch of the device, and means on the base member for securing the device in place.
2. A sound producing device comprising the combination of a reed unit, and a hollow body on which said reed unit is positioned, said body having an integral tubular member which serves for the purpose of forming an air passage for said body, and also for securing the device to an appurtenance adapted to vibrate the reed of said unit, and said body consisting of sections adjustable to a fixed relation for the purpose of changing the sound pitch of the device.
3. A sound producing device comprising the combination of a reed unit, and a hollow body having spaced integral ribs, said unit being positioned between and secured to said ribs, and said body having an integral tubular member, which serves for the purpose of forming an air passage for said body, and also for securing the device to an appurtenance adapted to vibrate the reed of said unit.

Signed at New York, in the county of New York, and State of New York, this 30th day of September, A. D. 1929.

CHARLES F. HANSELMANN.
